ROBERT C. SPRAGUE, OF QUINCY, MASSACHUSETTS, ASSIGNOR TO SPRAGUE SPECIAL-TIES CO., OF QUINCY, MASSACHUSETTS, A CORPORATION OF MASSACHUSETTS

ELECTRICAL CONDENSER AND METHOD OF MAKING THE SAME

Application filed December 13, 1927. Serial No. 239,684.

This invention is particularly applicable to condensers such as that disclosed in my companion application Serial No. 135,342, filed September 14, 1926, of which this application is in part a continuation, but it is to be understood that the present invention is applicable to other condensers as well.

Objects of the invention are to provide a condenser which is simple and economical to construct but which is efficient and durable in use, which does not require a metal container or other housing such as ordinarily employed, which has an effective and permanent electrical contact between the terminals and conductive layers, which has durable terminals permanently anchored in the body of the condenser so as not to break off or pull out, which is free from the likelihood of short circuit, and generally to improve the art of condensers.

Prior to the invention of the aforesaid application it was customary to house condensers of the wound foil type in a tin can or other rigid container and to mount the condenser terminals on the container, the wound condenser inside the container merely being provided with light terminal strips for connecting the foil strips with the terminals on the container. This practice has not only greatly increased the cost of material and labor in the process of manufacture, but it has added largely to the bulk and weight of the resulting product. Moreover, the aforesaid terminal strips connecting the foil strips with the container terminals have been very thin, being little if any heavier than the foil windings, so that they often tear off or pull out in assembling or repairing a condenser, the strips necessarily being soft and thin to avoid cutting the foil wound therearound.

According to my invention, the container and second set of terminals carried thereby are eliminated by mounting heavy terminal strips directly in the body of the condenser

in such a way that they do not tend to puncture the insulating strips between the foil strips, do not pull out, and therefore serve as the ultimate terminals of the condenser, even to the extent of supporting the condenser as is often desirable in radio sets. This is accomplished by pressing the relatively heavy terminal strips into recesses in a core of fiber-board or the like, or by striking up projections on the terminal strips which either pinch the core or wedge into recesses previously formed in the core. The inner ends of the foil strips are preferably inserted under the terminals respectively before the latter are pressed into the core, thereby anchoring the ends of the foil strips (and their intermediate insulating strips to the core) which greatly facilitates the process of winding the strips on the core.

Another unique characteristic of this invention consists in arranging the terminal strips obliquely in approximately parallel offset relationships so that they may extend a greater distance into the condenser, on the same side of the core, if desired, and at the same time project from the ends of the condenser approximately midway between the sides or lateral edges, thereby protecting the projecting portions from accidental breakage and facilitating the mounting of the condenser by means of the terminals.

Other objects and advantages of the present invention will be evident from the following description and preferred embodiment illustrated in the accompanying drawings, in which

Fig. 1 is a plan view of the condenser core;

Fig. 2 is a section on line 2—2 of Fig. 1;

Fig. 3 is a plan view of terminal member;

Fig. 4 is a section on line 4—4 of Fig. 3;

Fig. 5 is a plan view of a partially completed condenser, showing one terminal and one set of foil and insulating strips applied to the core;

Fig. 6 is a similar view showing the end of the first set folded over and the second set of foil and insulating strips, together with the second terminal, applied;

Fig. 7 is a view similar to Fig. 6 showing the second set of foil and insulating strips folded over preparatory to winding both sets around the core in the same direction;

Fig. 8 is a section on line 8—8 of Fig. 7;
Fig. 9 is a central transverse section of the completed condenser; and

Fig. 10 is a central longitudinal section of a slightly modified condenser having a greater number of turns and having differently shaped terminals.

The particular embodiment of the invention chosen for the purpose of illustration comprises a core C formed of fiber board or other suitable material and having in one face thereof two oblique grooves 1 and 2 meeting the ends of the core approximately midway between the lateral edges. In addition to the recesses 1 and 2 the core also has recesses 3 and 4, preferably extending all the way through the core, to receive prongs or other projections on the terminals.

The terminals may be shaped in various ways depending upon the way the condenser is to be mounted or connected in circuits but in general they are preferably characterized by a thickness depending upon the rigidity required, the depth of the grooves 1 and 2 being made to correspond, by prongs tightly fitting in the recesses 3 and 4, and by end projections which are oblique to the portions fitting in the grooves so as to project at right angles to the ends of the core. A typical terminal is shown in Figs. 3 and 4 comprising a body portion 5 adapted to fit in one of the grooves of the core, struck up prongs 6 adapted to fit in the recess 3 or 4 and an oblique end projection having an opening 7 for connection to a circuit and an opening 8 for mounting the terminal. The terminal is preferably formed of relatively stiff metal, such as copper of sufficient thickness to render the terminal fairly stiff, and the prongs 6 are preferably tapered so as to wedge tightly in the openings 3 or 4.

The conducting and insulating strips are preferably in the form of very thin metal foil tissue paper lightly cemented together with paraffin or other suitable adhesive, as disclosed in my aforesaid application, so that these strips may be readily wound as a single composite strip, each comprising a foil strip and one or more paper strips. It will of course be understood that the foil of one set will contact with one terminal and the foil of the second set with the other terminal. In Figs. 5 to 10 the foils of the two strips are designated F and F' and the paper component as P and P'.

As shown in Fig. 5, one set of foil and

paper strips is first applied to the core and one terminal is then applied over the set of strips with the paper next to the core and the foil contacting with the terminal. Upon pressing the terminal into the groove the prongs 6 puncture the strip and embed themselves in the recesses 3 tightly enough to hold the parts together during the succeeding operations in winding the condenser. The inner end of the strip, which is preferably cut obliquely as shown in Fig. 5, is then folded over the terminal T, thereby to establish good electrical contact between the foil and both sides of the terminal as well as to protect the succeeding turns of the winding by virtue of the folded-over ends between the terminal and the succeeding windings. After the first strip and terminal have been applied as described, the second terminal and strip are similarly applied as illustrated in Figs. 6, 7 and 8. The two composite strips P—F and P'—F' are then wound around the core clockwise (Fig. 8) until the composite strips have been completely wound around the core. The outer end of the inner strip P—F is then folded outwardly under the outer end of the outer strip P'—F' as shown in Fig. 9 so that the foil F' of the outer strip can not contact with the foil F of the inner strip at the end of the outer strip as it otherwise might do if the foil F' of the outer strip were slightly longer than the taper P' of the outer strip.

After the composite strips have been completely wound as aforesaid an insulating wrapper W is applied over the composite strips. This wrapper is a relatively heavy sheet of paper thoroughly waterproofed as with asphalt, as described in my aforesaid application. The condenser is then preferably dipped in high temperature paraffin to drive out all the air and to thoroughly impregnate the condenser, whereupon it is transferred to a cooler bath of paraffin to reduce the temperature of the impregnation material to the point where it will not run out when the condenser is finally removed. The condenser is then preferably compressed to drive out excess impregnation material and reduce it to a standard thickness and, after the exterior of the condenser and the projecting portions of the terminals have been cleaned, the condenser is ready for use.

In the modification shown in Fig. 10 the terminals are made somewhat longer and are so shaped that the condenser may be mounted on a flat surface by means of the terminals as is oftentimes desirable in radio practice. Fig. 10 also illustrates the fact that the wrapper W is somewhat longer than the width of the composite strips, preferably being substantially equal to the length of the core, so that the space at each end of the wound strips may be filled with

paraffin or other suitable sealing material as indicated at S.

From the foregoing it will be evident that this condenser may be readily and economically constructed and does not require any metallic container to carry the terminals by which the condenser is to be connected in circuit by virtue of the unique construction whereby the main terminals are securely anchored in the body of the condenser.

I claim:

1. A condenser comprising a flat body of alternate layers of insulating and conducting material, and two terminals extending obliquely to the lateral edges of the body in approximately parallel offset relationship and projecting respectively from the opposite end edges of the body approximately midway between the lateral edges.

2. A condenser comprising two terminals with insulated layers of foil wrapped therearound, the terminals extending obliquely in approximately parallel offset relationship within the body of foil and projecting approximately centrally from opposite ends of said body.

3. A condenser comprising a core having terminal recesses extending obliquely to the lateral edges in offset relationship and meeting the end edges approximately midway between the lateral edges, terminals disposed in said recesses and projecting from the end edges of the core, and insulated layers of foil wrapped laterally around said core with their inner ends respectively extending into said recesses under said terminals.

4. A condenser comprising a core having terminal recesses extending obliquely to the lateral edges in offset relationship and meeting the end edges approximately midway between the lateral edges, terminals disposed in said recesses and projecting from the end edges of the core, and insulated layers of foil wrapped laterally around said core with their inner ends respectively extending into said recesses under said terminals and thence folding over the terminals.

5. A condenser comprising a core having terminal recesses in its periphery, terminals disposed in said recesses, and insulated layers of foil wrapped around said core with their inner ends respectively extending into said recesses under said terminals and thence folding back over the terminals and thence over said periphery.

6. A condenser comprising a core having sets of superposed insulating and foil strips wound therearound, the inner ends of one set being folded foil to foil under the inner ends of the other set and the outer ends of one set being similarly folded under the outer ends of the other set.

7. A condenser comprising a core having sets of superposed insulating and foil strips

wound therearound, the inner ends of each set being folded foil to foil and the outer ends of one set being similarly folded under the outer ends of the other set.

8. A condenser comprising a core having two sets of superposed insulating and foil strips wound therearound in the same direction with the foil strip outermost in each set, and the outer end of the inner set being folded outwardly foil to foil under the outer end of the outer set.

Signed by me at Quincy, Massachusetts, this 8th day of December, 1927.

ROBERT C. SPRAGUE.
